UNITED STATES PATENT OFFICE.

JOHN J. SHERMAN, JR., OF CHICAGO, ILLINOIS.

DESIGN FOR A GAME-BOARD.

SPECIFICATION forming part of Design No. 85,718, dated February 11, 1902.

Application filed January 6, 1902. Serial No. 88,702. Term of patent 14 years.

To all whom it may concern:

Be it known that I, JOHN J. SHERMAN, Jr., a citizen of the United States, residing at Chicago, in the county of Cook and State of Illinois, have invented and produced a new and original Design for a Game-Board, of which the following is a specification, reference being had to the accompanying drawings, forming a part thereof.

Figure 1 is a plan view of a game-board of my new and original design; Fig. 2, a front elevational view of the same, and Fig. 3 a section taken as indicated at line 3 of Fig. 1.

As shown in the drawings, the leading or material feature of my design consists in a rectangular-shaped open box having front and rear ends a a' , sides a^2 a^3 , a block a^4 at the center of the front end, rearwardly-divergent straight partitions a^5 , flanking the block a^4 , forwardly-convergent partitions a^6 , separated by spaces a^7 from the partitions a^5 , pins a^8 in alignment with said partitions, forwardly-convergent partitions a^9 , meeting at a point a^{10} in the longitudinal center line of the board, rearwardly-convergent partitions a^{11} , adjoining the rear ends of the partitions a^9 , rearwardly-convergent partitions a^{12} , sepa-

rated by spaces a^{13} from the partitions a^{11} , posts a^{14} in said spaces, and rearwardly-convergent partitions a^{15} , separated by spaces a^{16} from the partitions a^{11} . 30

Minor features of my design are the vertical slot b , cutting the front end a and block a^4 , the bisected vertical groove b' at the rear edge of said block, the bisected horizontal perforation b^2 near the bottom of the slot b , the spots or dots c at four corners of a centrally-located square, a central spot or dot c' , a spot c^2 in each front corner pocket, a spot c^3 in each rear corner pocket, and a spot c^4 in the central rear pocket. 40

Having described my invention, what I regard as new, and desire to secure by Letters Patent, is—

The design for a game-board as herein shown and described. 45

In testimony whereof I have signed my name to this specification in the presence of two subscribing witnesses.

JOHN J. SHERMAN, JR.
